FLUORESCENT LAMP

David Hess, New York, N. Y., assignor to Kate Lowenberg, New York, N. Y.

Application December 9, 1940, Serial No. 369,302

2 Claims. (Cl. 240—81)

The present invention relates to portable fluorescent lamps and its object is to provide a lamp particularly adapted for draftsmen, designers, colorists, and for those purposes requiring the throwing of fluorescent light from various angles and positions upon objects somewhat closely associated with the fluorescent source of light. The basis of the invention is the formation of a reflector and fluorescent lamp carrier independently of the transformer, the mounting of the same upon a flexible goose neck rising from a base member which encloses the transformer and is rendered stable by the weight of the latter and that of the base member, the arrangement being such that the reflector with the lamp carried thereby may be moved independently of the transformer over a wide range of positions relative to the transformer and toward and from the work under preparation or examination without movement of the transformer.

The invention will be described with reference to the accompanying drawing, in which:

Figure 1 is a view in side elevation illustrating an embodiment of the invention, certain elements being shown by dotted lines.

Figure 2 is a view similar to Figure 1 in front elevation.

Figure 3 is a transverse sectional elevation on the line 3—3, Figure 2.

Figure 4 is a fragmentary vertical section on the line 4—4, Figure 3.

Figure 5 is a top plan view of the reflector, the lamp and connecting elements being shown in dotted lines, the goose neck connection being shown in full lines and connected to the reflector to the left of its center as compared with the construction in Figure 2.

Referring to the drawing, I have shown at 1 a transformer enclosing base member, the transformer being indicated by dotted lines at 2. In the present embodiment base member 1 is formed as a box having a bottom closure plate 1x to which are attached depending supporting feet 3. At the top of the box is a switch member 4 controlling the wiring which is shown diagrammatically at 5.

The top of the box is apertured for the passage of four wires 5 comprising two cathode and two anode wires, one set, to wit, a cathode and an anode wire being required for each contact end of the fluorescent lamp. Secured to the top of the box and surrounding the wire aperture therein is a tubular connector 6 for a flexible goose neck 1 which is of the same structural formation as the customary BX electrical conduit in com-

mon use, but which in practice will be made up with a decorative plating or coating as, for example, with a chromium plating or an enamel finish.

At the upper end of the goose neck 1 the latter may carry a connector 8 secured to the back wall of reflector 9. In Figures 1 and 2 the point of connection between the goose neck and the reflector is at the center of the latter. The reflector 9 may be of any suitable formation as to the position and relation of its reflecting surfaces for the fluorescent lamp 10 carried thereby. The back wall 9x of the reflector is apertured to receive two spaced contact posts 11 carrying spaced contacts 12 for the cathode and anode post leads 13 of the fluorescent lamp 10. At the rear of wall 9x each contact post 11 is formed with a right angular extension 11x apertured to receive a screw bolt 14, the latter passing through wall 9x and through a cap plate 15 which encloses the posts and the wiring therebetween, the cap plate being held in position by nuts 16 threaded on screw bolts 14 as shown more particularly in Figure 3. Each of the right angular extensions 11x of posts 11 receives cathode and anode conductor screws for appropriate cathode and anode wires 5, the conductor screws being indicated at 17, Figure 4.

In the construction of Figure 5, the connection between the goose neck 1 and the reflector is toward the left hand end of the latter and by means of any suitable ball or universal connection indicated at 18. Such ball connections are well known in the mechanical art and do not require specific description or illustration. There are certain advantages in the structure of Figure 5. For example, the major area of the fluorescent lamp may be brought down toward the work by swinging the reflector downwardly without changing the position of the goose neck, and a greater range of angular adjustment is permitted.

By means of the invention, a fluorescent lamp may be conveniently employed in all cases where it is required that articles on a supporting table be illuminated for examination or work with the fluorescent rays thrown upon the respective article from various angular adjustments of the lamp quickly and easily obtained without changing the position of the relatively heavy transformer and whilst maintaining the full stability of the device.

A further and more important use of the invention is in connection with sewing machines. Thus the lamp may be carried by a bracket secured to the sewing machine head and the position of the reflector with the fluorescent lamp carried thereby may be quickly adjusted to throw

fluorescent rays in accordance with the particular nature of the sewing machine and conditions of general illumination.

Having described my invention, what I claim and desire to secure by Letters Patent, is as follows:

1. In fluorescent lamps, a base member comprising a casing, a transformer therein, a hollow flexible goose neck carried by the casing, cathode and anode wires leading through the goose neck to the transformer, a ray-reflecting carrier at the outer end of the goose neck, cathode and anode posts within the reflector, one at each end thereof, each post being formed with a right angular extension aperture to receive a screw bolt, the angular extension of the posts extending rearwardly of the reflector, a longitudinally extending housing at the rear of the reflector, bolts passing through the reflector and the angular extensions of the posts and secured to the housing, contacts carried by the posts within the reflector and connected to said wires, the wires being led through the said housing and a fluorescent lamp held by the reflector and having contact leads engaging said contacts, whereby the 25

ray-reflecting carrier and lamp held thereby may be moved to various positions relatively to the transformer.

2. In fluorescent lamps, a transformer and a 5 ray-reflecting fluorescent lamp carrier having cathode and anode contacts for engagement with the cathode and anode leads of a fluorescent lamp, a hollow flexible carrier intermediate the transformer and the ray-reflecting carrier and supporting the latter upon the transformer and conductor wires leading from the transformer through said hollow flexible carrier and to the contacts of the ray-reflecting carrier, the point of connection between the flexible hollow carrier 10 and the ray-reflecting carrier being near one end of the latter and the means of connection being a universal swivel formed as a conduit and enclosing protection medium for the conductor wires led through the hollow flexible carrier and 15 leading to the contacts of the ray-reflecting carrier, whereby the ray-reflecting carrier and lamp held thereby may be moved to various positions relatively to the transformer.

DAVID HESS.
